UNITED STATES PATENT OFFICE.

PETER MILLER, OF SPRINGDALE, WASHINGTON.

TIE-PULLER.

Specification of Letters Patent. Patented Dec. 20, 1921.

1,400,692.

Application filed May 12, 1921. Serial No. 468,804.

To all whom it may concern:

Be it known that I, PETER MILLER, a citizen of the United States, residing at Springdale, in the county of Stevens and State of Washington, have invented certain new and useful Improvements in Tie-Pullers, of which the following is a specification.

The present invention relates to improvements, in tie pullers for use in the construction and repair of railway road-beds, especially adapted for removing and replacing railway ties. The primary object of the invention is the provision of hand operated mechanism for pulling the tie out of or into position in the road bed, which mechanism is comparatively simple in construction and operation, inexpensive in cost of production, and readily adapted for attachment to the fixed railway rail as a support. To this end the invention consists essentially in a portable device involving novel combinations and arrangements of the supporting frame and duplex capstan, together with temporary attaching means for use in connection with the rail, as will be hereinafter more specifically set forth.

In the accompanying drawings I have illustrated one complete example of the physical embodiment of my invention wherefore in the parts are combined and arranged according to the best mode I have thus far devised for the practical application of the principles of my invention.

Figure 1 is a perspective view showing a portion of a railroad with the tie puller of my invention shown in operative position for pulling a tie from the roadbed.

Fig. 2 is a view in end elevation of the mechanism.

Fig. 3 is a view in side elevation of the mechanism showing especially the attachment to the rail.

In the preferred form of the invention as shown in the drawings I have illustrated the roadbed or railroad as composed of the ties T, with the usual rails R and indicated the railhead as R'. The supporting frame for the duplex capstan is preferably of cast or wrought metal having a main, vertically disposed plate 1 from which project lateral flanges 2, 2, these parts preferably being open as shown to combine strength with lightness in weight in order that the appliance may be transported or carried with facility by using the end handles H H.

The main plate is generally rectangular in

shape but has a lower open central portion with a straight or flat horizontal face 3 adapted to rest upon the top surface of a tie as in Figs. 1 and 2, to provide the main support for the appliance when in operative position near the end of the tie. The frame is located at the outer side of the rail and the lateral flanges 2 project toward the rail, with the extension or jaw 4 on the flange 65 adapted to engage the under side of the rail base, a horizontal slot or recess 5 being provided in each of the lateral flanges above the jaw 4 to engage over the outer flange of the rail base, as best seen in Fig. 3. After 70 the appliance has been properly placed with its recesses 5 engaged over the rail-base flanges and the lower jaws 4 beneath the rail base, a pair of hooked detents 6, which are pivoted at 7 on the lateral flanges, are 75 turned down over the rail head R' as seen in Fig. 3. The free edge of the lateral flanges is also notched at 5' to fit up under one side of the rail head, and it will be seen that by utilizing the jaw 4, recess 5, notch 80 5' and detent 6 on each of the lateral flanges, the appliance with facility may quickly be attached to or detached from the rail. The presence of the recess 5 and the notch 5' in the edge of the two lateral flanges provides 85 for a brace or lug for engagement with the rail, which engagement, together with the support of the main plate through its surface 3 on the top of the tie, provides for a rigid and well braced anchorage of the capstan frame for operation of the device.

The duplex capstan includes a pair of vertically disposed spindles 8, one located at each side of the supporting tie and journaled in bearing lugs 9, 9 which project from 95 the respective ends of the main frame plate toward the center thereof, the upper ends of the spindles being journaled in openings therefor in the top plate 9' of the frame. Each spindle has a drum 10 secured thereto 100 and located between the pairs of perforated bearing lugs 9, 9, and a cable, as 11 or 12 with its ends attached to the drums are provided to be wound upon the drums, the loop of the cable may be passed over the end of 105 the tie to which power is to be applied. At the upper end of each spindle, and located above the top plate 9' is a pinion as 13, and between these pinions is interposed a master gear wheel 14, the spindle of which is journaled in the top plate 9' and the head 15 of the spindle has a bar or lever 16 to be in-

serted in one of the openings 17 therein to turn the master wheel.

- The construction and operation of the appliance will be apparent from the drawing and description, and in Fig. 1, where the device is illustrated in position to remove a tie from the road bed, the spikes have been removed from the tie, the cables 11 and 12 have been connected at the distant end of 10 the tie, and by turning the capstan bar or lever 16 the pinions 13 and their drums 10 may be revolved to wind the cables on the drums and thus pull the tie laterally of the roadbed to remove it therefrom, thus saving 15 time and labor otherwise required for similar operations.
- Having thus fully described my invention, what I claim and desire to secure by Letters Patent is—
- 20 1. The combination in a tie puller as described with a supporting frame comprising a main plate and a duplex capstan with operative cables supported therein, of lateral flanges on said plate each having a lug for engagement with a rail, a jaw to engage be-
- 25

neath the rail and recessed and notched as described, and a hooked detent pivoted on each flange to engage the rail head.

2. The combination in a tie puller with a frame comprising a main plate having a surface for support on a tie, of laterally extending flanges on said plate each provided with a projecting jaw to fit under a rail, said flanges having recesses and notches forming a brace lug for engagement with a rail, and a pivoted, hooked detent on each flange to engage over the rail head for the purpose described.

3. The combination with a main plate, of a pair of spaced spindles supported therein 40 each having a drum, a cable on each drum and connecting means at the free ends of the cables, a pinion for each spindle, a master gear engaging said pinions and means for revolving said gear, lateral flanges on 45 said plate, and means on said flanges for temporarily attaching said plate to a rail.

In testimony whereof I affix my signature.

PETER MILLER.
